CLAIM

The ornamental design of an inspection device, substantially as shown and described.

DESCRIPTION

FIG. 1 is a front top perspective view of an inspection device showing the new design;

FIG. 2 is a left side elevation view thereof, the right side view being similar;

FIG. 3 is a back elevation view thereof;

FIG. 4 is a top plan view thereof, the bottom view being similar;

FIG. 5 is a front elevation view thereof; and,

FIG. 6 is a front side perspective view thereof.

The broken lines shown in the drawings are included for the purpose of illustrating environmental structure and form no part of the claimed design.
